DESIGN FOR A STRETCHABLE BRAID

Milton S. Mindell, New York, N. Y.

Application April 27, 1940, Serial No. 91,990

Term of patent 3½ years

To all whom it may concern:

Be it known that I, Milton S. Mindell, a citizen of the United States of America, residing in the city of New York, county of New York, and State of New York, have invented a new, original, and ornamental Design for a Stretchable Braid, of which the following is a specification, reference being had to the accompanying drawing, forming part thereof.

Fig. 1 is a plan view of a stretchable braid showing my new design.

Fig. 2 is an enlarged view thereof.

I claim:

The ornamental design for a stretchable braid, substantially as shown.

MILTON S. MINDELL.
